UNITED STATES PATENT OFFICE.

RUSSELL WILES, OF CHICAGO, ILLINOIS, ASSIGNOR TO JOHN W. PAGE, OF CHICAGO, ILLINOIS.

EXCAVATING-SCOOP.

No. 852,863.

Specification of Letters Patent.

Patented May 7, 1907.

Application filed September 8, 1906. Serial No. 333,769.

To all whom it may concern:

Be it known that I, RUSSELL WILES, a citizen of the United States, residing at Chicago, in the county of Cook and State of Illinois, 5 have invented a new and useful Excavating-Scoop, of which the following is a specification.

My invention relates to improvements in excavating scoops, and is fully described and 10 explained in this specification and shown in the accompanying drawings, in which

Figure 1 is a side elevation of my improved scoop and Fig. 2 is a top plan thereof.

Referring to the drawings, A is a suitable 15 shovel, which is pivotally secured to and supported by a supporting bail, B, the pivotal connection between shovel and bail being behind the center of gravity of the shovel, so that when the shovel is released its forward 20 end will swing downward to dump its contents. The supporting bail, B, carries at its upper end two sheaves, over which pass ropes, C, the lower ends of which are connected to a ring or other suitable fastening device, 25 a, secured to a bridge which extends across the front end of the shovel, said ropes being led from said ring over the sheaves and thence outward through eyes, a¹, at the front corners of the shovel, and thence forward, 30 where they are joined together at c, being continued from their junction point in the form of a single hauling-rope, which runs over the winding drum of an engine or other suitable power device. Each of the ropes, C, 35 is provided with a button, c', between the eye through which it passes and the sheave over which it runs, said button being in such position on the rope that when it is in contact with the eye the shovel will be in substantially 40 a horizontal position.

In the operation of my improved scoop the scoop is drawn forward through the material to be operated upon by means of the hauling-rope, and during this portion of the operation the buttons will be drawn against the eyes so that the propelling force will be exerted upon the shovel by the buttons, and the shovel will be held in a substantially horizontal position by means of the ropes which connect the buttons with the eye, a¹, on the shovel. After the shovel has been filled it is raised by means of the supporting bail and moved to the position where it is desired to

dump it, the hauling-rope being maintained taut to hold the shovel horizontal. When it 55 is desired to dump the shovel the tension of the hauling-rope is released and the shovel swings down, the buttons simultaneously moving up toward the sheaves and the ropes sliding through the eyes. 60

It will be observed that this construction is exceedingly simple and accomplishes its purpose without certain of the complexities of other forms of scoops now in use. It will also be observed that the eyes, a¹, are curved, 65 as shown in the drawings, so as to conform to the course of the ropes and are flared outward at their ends so that no sharp angles will be presented to the ropes whereby undue and unnecessary friction will be exerted 70 thereon.

I realize that considerable variation is possible in the details of this construction, without departing from the spirit of my invention, and I do not intend, therefore, to limit 75 myself to the specific form herein shown and described.

I claim as new and desire to secure by Letters Patent:—

1. The combination with a shovel having 80 a cutting edge at its forward end and a supporting bail pivoted to the shovel behind the center of gravity thereof, of a hauling-rope and stationary device on the front of the shovel through which said rope passes, said 85 rope having a connection with the supporting bail and an engagement device on the rope adapted to coöperate with the portion of the shovel through which the rope passes, to limit the relative movement of the rope 90 therethrough.

2. The combination with a shovel having a cutting edge at its front end and a supporting bail pivoted thereto behind the center of gravity thereof, of eyes secured to the shovel, 95 ropes passing through said eyes and having connection with the hauling-bail, and projections on the ropes adapted to engage the eyes.

3. The combination with a shovel having 100 a cutting edge at its forward end and a supporting bail pivoted thereto behind the center of gravity thereof, of an eye on the shovel, a rope passing therethrough, a sheave secured to the supporting bail, over which 105 sheave the rope passes, said rope being se-

cured to the shovel in front of its pivot, and a suitable engagement device upon the rope to engage the eye.

4. The combination with a shovel having a cutting edge at its forward end and a supporting bail pivoted thereto behind the center of gravity thereof, of eyes at the front of the shovel, sheaves on the supporting bail, ropes passing through the eyes and over the sheave and secured to the shovel in front of its pivot, and projections upon the ropes adapted to engage the eyes.

5. The combination with a shovel having a cutting edge at its forward end and a supporting bail pivoted thereto behind the center of gravity thereof, of sheaves on the sup-

porting bail, curved eyes at the front of the shovel, the upper ends of which point toward the sheaves and the lower ends of which point forward, ropes passing through the eyes and over the sheaves and having connection with the shovel in front of its pivot, and stops on the ropes adapted to engage the eyes.

In witness whereof, I have signed the above application for Letters-Patent at Chicago, in the county of Cook and State of Illinois, this 5th day of September, A. D. 1906.

RUSSELL WILES.
